UNITED STATES PATENT OFFICE.

JOHN H. GOEHST, OF CHICAGO, ILLINOIS.

DESIGN FOR A SUPPORT AND REFLECTOR FOR ELECTRIC LAMPS.

SPECIFICATION forming part of Design No. 35,102, dated September 17, 1901.
Application filed May 20, 1901. Serial No. 61,196. Term of patent 3½ years.

To all whom it may concern:

Be it known that I, JOHN H. GOEHST, a citizen of the United States, residing at Chicago, in the county of Cook and State of Illinois, have invented and produced a new and original Design for a Support and Reflector for Electric Lamps, of which the following is a specification, reference being had to the accompanying drawing, forming part hereof.

10 The drawing is a perspective of an electric-lamp support and reflector embodying my novel design.

An electric-lamp support and reflector made in accordance with and embracing the features of my novel design comprises an upwardly-flaring hollow body having the general form of an inverted bell, which is circular in cross-section, and a base which is made of greater diameter than said body at the junction of said body and base and irregularly tapers toward its lower end. At the junction of the body with the base and rising from the base is a circular rib or band having elongated openings or depressions in its side and which surrounds said body. Radially outside of said rib is an annular generally horizontal surface, and said annular sur-

face is surrounded by a vertical flange which rises a distance above the annular horizontal surface. The space between said rib or band and annular flange forms, in effect, a shallow upwardly-opening annular groove at the upper end of the base which surrounds said body. The horizontal surface is provided with a plurality of uniformly and annularly disposed holes or openings.

The main or characteristic feature of my novel design embraces the upwardly-flaring symmetrical hollow body, having a base provided in its upper part with a perforated generally horizontal annular surface located between the outer vertical annular flange and the inner rib or band, which latter surrounds said body.

I claim as my invention—

The design for a support and reflector for electric lamps substantially as herein shown and described.

Signed at Chicago, Illinois, this 15th day of May, A. D. 1901.

JOHN H. GOEHST.

In presence of—

WILLIAM L. HALL,
GERTRUDE BOYCE.
